SPECTACLE FRAME

Alexander Kono, Forest Hills, N. Y.

Application March 23, 1950, Serial No. 8,721

Term of patent 14 years

(Cl. D57—1)

To all whom it may concern:

Be it known that I, Alexander Kono, a citizen of the United States, residing at Forest Hills, in the county of Queens and State of New York, have invented a new, original, and ornamental Design for a Spectacle Frame, of which the following is a specification, reference being had to the accompanying drawing, forming part thereof.

In the drawing:

Fig. 1 is a front view of a spectacle frame showing my new design;

Fig. 2 is a side view of said frame;

Fig. 3 is a top view of the frame; and

Fig. 4 is an enlarged sectional view taken substantially along the line 4—4 of Fig. 1.

I claim:

The ornamental design for a spectacle frame, substantially as shown.

ALEXANDER KONO.
